NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

CYLINDER-LOCK.

1,141,463.

Specification of Letters Patent. Patented June 1, 1915.

Original application filed July 3, 1914, Serial No. 848,845. Divided and this application filed December 12, 1914. Serial No. 876,757.

To all whom it may concern:

Be it known that I, NORMAN B. HURD, a citizen of the United States, residing at New Britain, county of Hartford, State of Connecticut, have invented certain new and useful Improvements in Cylinder-Locks, of which the following is a full, clear, and exact description.

This invention relates to cylinder locks and is designed to provide an operating roll-back or cam having at least three positions relative to the rotatable element or plug of the cylinder lock, means being provided for normally holding this cam in one of said 15 positions, certain keys being designed to position this cam in the other positions. This invention constitutes a division of my application Serial No. 848,845, filed July 3rd, 1914. Such a roll-back will afford a plurality of controls, as will be obvious.

A preferable embodiment of the invention is described in detail in the following specification and is illustrated in the accompanying drawings forming a part thereof, in 25 which.—

Figure 1 is a view in side elevation, partly in section, of a cylinder lock embodying the present invention. Fig. 2 is an end elevation of the parts shown in Fig. 1. Figs. 3-5 30 show views of the three classes of keys co-operating with the cylinder lock.

Referring to these drawings by numerals, 1 indicates the usual casing of the cylinder lock and 2 the usual rotatable element or 35 plug therein, which element co-operates with a series of spring-pressed pin-tumblers (not shown) as usual in cylinder locks. The inner end of the plug is reduced and shouldered, as at 2^a, to receive thereon a fixed 40 roll-back 4 having a recess at its lower end whereby it may fit over the shouldered end 2^a of the plug. The usual keyhole slot 3 extends through the plug, the recess at the inner face of the roll-back 4 being in line with 45 this keyhole slot. The inner face of the roll-back is channeled as at 5 and is provided with opposite vertical grooves 6 therein, within which is mounted a vertically sliding plate 7 carrying at its upper 50 end, and offset laterally from the body of the fixed roll-back 4, a relatively movable head forming a second roll-back 8. The lower end of the plate 7 is offset in a horizontal plane forming a strike or abutment

surface 9, the extremity of this offset portion being turned downwardly again to provide a second abutment or strike surface 10 below the first abutment 9, both of these abutments being in the line of the keyhole slot 3 in the normal position of the plate 7. 55 This normal position of the plate 7, in the present embodiment, is its lowermost position, the body of the fixed roll-back or cam 4 being recessed, as at 11, to provide a spring-pocket or groove, housing a coiled 60 spring 12, whose upper end bears against the body of the roll-back, and whose lower end engages a pin 13 carried by and extending outwardly from the forward face of the plate 7. This spring normally presses the 65 pin 13 against the upper face of the extension 2^a of the plug and holds the plate 7 and the second cam or roll-back 8 in the lowermost position of the three positions, 70 relative to the first cam or fixed roll-back 4. 75 The plate and second cam are movable in the guideways 6 into second and third positions, through the co-operation therewith of certain keys.

A plurality of different types of keys co-operate with this cylinder lock, such keys being designated A, B, C, and at least two of these classes of keys being longer than the others and of different relative lengths. As will be seen in the drawings, Figs. 4 and 85 5, the keys of the classes B and C are longer than the keys of class A and are of different relative lengths.

As I have before stated, the two abutments or strike surfaces 9 and 10 are in the 90 line of the keyhole slot 3. They are positioned, however, so that keys of the class "A" type or "short" keys are not of sufficient length to extend through the plug-slot to engage these abutment surfaces. 95 Consequently, with a key of the class A, the fixed roll-back 4 may be rotated with the second roll-back 8 in one (and its normal) position relatively thereto. Keys of the class B type, however, are of sufficient length to 100 engage the strike surface 9, but not sufficiently long to engage the second strike surface 10. Consequently if a key of the class B type is used, its end will engage the strike surface 9 and lift the plate 7 and second 105 roll-back 8 into a second position relative to the fixed roll-back 4, which second position may be utilized to control certain spe-

cial mechanism in the lock case. Keys of the class C type are longer than keys of the B type and are of such length that when inserted in the key-slot 3 of the plug they will engage with the second abutment surface 10 and lift the plate 7 and second roll-back 8 to third position, and therefore may be utilized to control still other mechanism within the lock case.

10 It will be evident that I have provided a cylinder lock mechanism wherein a movable roll-back is arranged to be given a plurality of controlling positions by a plurality of keys of different lengths, there being at least three different positions for the roll-back and at least two long keys of different relative lengths. Such a mechanism will provide a plurality of controls for mechanism within a lock case and will tend to 15 simplify the lock mechanism proper by placing control in the cylinder lock itself.

It will also be evident that while I have herein described a specific embodiment of my invention, the same is susceptible of variation both in structure and in relative arrangement of parts within the spirit of the invention and the scope of the appended 20 claims.

What I claim is:

30 1. A cylinder lock comprising a casing, a rotatable element therein, a plurality of keys for rotating said element, a roll-back or cam operatively connected and rotated by the rotation of said element and having at least 35 three different positions radially thereof, with means normally tending to hold said cam in one of said positions, and means controlled by two different of said plurality of keys for moving said cam into a second and 40 third of said positions, respectively.

2. A cylinder lock comprising a casing, a rotatable element therein, a plurality of keys for rotating said element, a roll-back or cam carried by and rotating with said element 45 and having at least three different positions radially thereof, with means normally tending to hold said cam in one of said positions, and means controlled by two different of said plurality of keys for moving said 50 cam into second and third positions, respectively.

3. A cylinder lock comprising a casing, a rotatable element therein, a plurality of keys for rotating said element including at least 55 two keys longer than the others and of different lengths relatively, a roll-back or cam

carried by and rotating with said element and having at least three different positions radially thereof, with means normally tending to hold said cam in one of said positions, and with means controlled by said two longer keys for moving said cam into the second and third positions, respectively. 60

4. A cylinder lock comprising a casing, a rotatable element therein, a plurality of keys for rotating said element including at least two keys longer than the others and each of different lengths relatively, a roll-back or cam carried by and rotating with said element having at least two spaced abutments 70 and also having at least three different positions relative to said element with means normally tending to hold said cam in one of said positions, said two longer keys being adapted to engage said two abutments respectively to move said cam into second and 75 third positions, respectively.

5. A cylinder lock comprising a casing, a rotatable element therein, a plurality of keys for rotating said element, a roll-back 80 or cam fixedly connected to and rotating with said element, a second and relatively movable cam carried by and rotating with the first cam and having at least three different positions relative thereto, with means 85 normally holding said second cam in one of said positions, and with means controlled by two different of said plurality of keys for moving said second cam into second and 90 third positions, respectively.

6. A cylinder lock comprising a casing, a rotatable plug in said casing having a key-hole slot therein, a plurality of keys for rotating said plug including at least two keys longer than the others and of different 95 lengths relatively, a roll-back fixedly connected to and rotating with said plug and having an aligned key-slot therein, a second and relatively movable cam carried by and rotating with said first cam and having at 100 least three different positions relative thereto, with means normally holding said second cam in one of said positions, said cam having at least two spaced abutments normally positioned in the line of said key-slot and 105 arranged to be engaged by said two longer keys respectively, whereby said cam is moved into second and third positions.
